Primary Examiner — Eliza Z Bennett-Hattan(74) *Attorney, Agent, or Firm* — Sonya C. Harris; Invention Services(57) **CLAIM**

The ornamental design for the shower hook assembly, as shown and described.

DESCRIPTION

FIG. 1 is a front elevational view of my design; FIG. 2 is a right side elevational view of my design; FIG. 3 is a left side elevational view of my design; FIG. 4 is a bottom elevational view of my design; FIG. 5 is a top elevational view of my design; FIG. 6 is a top front right perspective view of my design, illustrating the environment of intended use of my design, wherein the dotted lines indicate an exemplary bathing environment and is not a part of my claimed design; and, FIG. 7 is a top front right perspective view of my design, illustrating intended use in its environment wherein the dotted lines indicating an exemplary bathing environment and is not a part of my claimed design. The broken lines in the drawings depict environmental subject matter only and form no part of the claimed design.
